UNITED STATES PATENT OFFICE.

WILLIAM VELTE AND JOHN FAGAN, OF PITTSBURG, PENNSYLVANIA.

IMPROVEMENT IN ICE-HOUSES.

Specification forming part of Letters Patent No. 101,405, dated March 29, 1870.

To all whom it may concern:

Be it known that we, WILLIAM VELTE and JOHN FAGAN, both of the city of Pittsburg, in the county of Allegheny and State of Pennsylvania, have invented a new and useful Improvement in Ice-Houses; and we do hereby declare that the following is a full, clear, and exact description thereof, reference being had to the accompanying drawings, and to the letters of reference marked thereon.

The nature of our invention consists in so constructing a house for freezing and packing ice that the boards which form the sides, roof, and one end of it may be turned on pivots so as to form a series of open spaces for the admission of cold air for the purpose of freezing in it blocks of ice.

To enable others skilled in the art to make and use our invention, we will proceed to describe its construction and operation.

In the accompanying drawings, which form part of our specification, Figure 1, Sheet 1, is a top view of our improvement in houses for freezing and packing ice, representing the lower part or body when the roof is removed. Fig. 2, Sheet 2, represents a vertical section of our improvement in houses for freezing and packing ice. Fig. 3, Sheet 2, represents the frames used for forming blocks of ice in the ice-house by freezing water in them. Fig. 4, Sheet 3, is a perspective view of our improvement in houses for freezing and packing ice. Fig. 5 is a side view of one end of the pivoted boards of the roof. Fig. 6 is a transverse section of same when cut through at line y' of Fig. 5.

In the accompanying drawings, A represents the frame for the body of the house. One end of this frame is provided with doors B.

In the frame A are pivoted boards e, the form of which is clearly shown in Figs. 1, 2, and 4. The boards are connected to a strip, x, by means of links o, so that by moving the strips x all the boards e of each series may be turned on their pivots. The boards are provided with a recess, i, which laps on the edge l of the board next to it, as clearly shown on the side of Fig. 1 marked B'.

The roof the house is formed of frame C and pivoted boards e', which are connected to the strips x' by means of links o'. In one of the gable ends of the roof should be made a small

door, as indicated by the dotted lines y. The ridge of the roof may be pivoted by a second roof, as indicated by the dotted lines s, and the rain may be carried off from the sides of the house by securing boards to the frame C of the roof, as indicated by the dotted lines m. The frame for forming the blocks of ice in the house consists of side pieces, D, and end pieces, f, which are held together by means of screw-bolts n, as shown in Fig. 3 of Sheet 2.

As the construction and arrangements of the several parts which form our improvement in ice houses will be readily understood from the foregoing description and by reference to the accompanying drawings, we will therefore proceed to describe the operation of filling it with ice.

The desired number of frames, such as represented in Fig. 3 of Sheet 2, is arranged on the floor, as shown in Fig. 1, Sheet 1. The boards e of the body of the building are then turned on their pivots so as to leave open space between them, as indicated in Fig. 1, Sheet 1, at the side marked A'. The boards e' of the roof are arranged in like manner. The frames for forming the blocks of ice are then filled with water by any suitable means. After it has frozen solid by the cold atmosphere of winter the screw-bolts n are then loosened up and the frames, jarred so as to free them from the blocks of ice, are then by means of suitable hoisting-gear attached to the staples 2 raised up, so as to bring the lower edge of it nearly up to the top of the blocks of ice. The screw-bolts are then tightened up and the frame is again filled with water, which is left in the frame until it has become frozen by the action of the cold atmosphere, and thus one block of ice is built upon the top of another until the house is filled.

In forming the blocks of ice in the frames we arrange the frames in the desired position on the floor of the house, and then with a sprinkling-can or other device sprinkle water along and on the several joints of the frames and let it freeze, thereby making them watertight. A thin sheet of water is placed in the frames and left standing until it has become congealed, then another thin sheet of water is congealed on top of the first, and thus one layer of ice after the other is formed until the frames are filled, which are then raised up in the man-

ner described, and the joints again closed by the sprinkling and freezing process, and a second block of ice formed upon the first, and thus one block is formed upon another until the house is filled.

The boards *e* of the body and the boards *e'* of the roof are closed with the recess *i* overlapping the edge *l* of the board forward of it, then the spaces between the blocks of ice and between the blocks of ice and the boards *e* or walls of the house are filled with sawdust or other suitable material for packing. The packing placed between the walls or boards *e* and the ice will hold the boards in a fixed and closed position. Having properly packed the ice in the body of the house, the upper surface of the ice is then covered with sawdust, straw, or other suitable material. The boards *e'* of the roof are then closed and secured by a brace

placed against one end of bars *X'*, which will thereby hold them in a fixed position. The packer then leaves the building through a small door, (indicated at *y*), which is then closed and secured.

A house or building constructed as herein-before described will answer for a skating-rink.

Having thus described our improvement in ice-houses, what we claim is—

The ice-house constructed as herein described, when used in combination with frames for filling the house with ice, substantially in the manner set forth.

WILLIAM VELTE.
JOHN FAGAN.
